US0D1039599S

(12) **United States Design Patent** (10) Patent No.: **US D1,039,599 S**
(45) Date of Patent: ** Aug. 20, 2024

(54) **ELECTRONIC CALCULATOR**

(71) Applicant: **CASIO KEISANKI KABUSHIKI KAISHA**, Tokyo (JP)

(72) Inventors: **Shunsuke Oka**, Tokyo (JP); **Kyohei Ishii**, Tokyo (JP)

(73) Assignee: **CASIO KEISANKI KABUSHIKI KAISHA**, Tokyo (JP)

(**) Term: **15 Years**

(21) Appl. No.: **29/827,255**

(22) Filed: **Feb. 18, 2022**

(30) **Foreign Application Priority Data**

(57) **CLAIM**

The ornamental design for an electronic calculator, as shown and described.

DESCRIPTION

FIG. 1 is a reduced-scale front, right side perspective view of an electronic calculator showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reduced-scale rear, left side perspective view thereof.

1 Claim, 7 Drawing Sheets
